UNITED STATES PATENT OFFICE.

GEORGE HENRY MAAS, OF MILWAUKEE, WISCONSIN.

HINGE.

No. 926,949.

Specification of Letters Patent.

Patented July 6, 1909.

Application filed December 18, 1908. Serial No. 468,123.

To all whom it may concern:

Be it known that I, GEORGE HENRY MAAS, a citizen of the United States, residing at Milwaukee, county of Milwaukee, and State 5 of Wisconsin, have invented new and useful Improvements in Hinges, of which the following is a specification.

My invention relates to improvements in hinges for shipping crates, and it pertains 10 more especially among other things, — first, to the peculiar construction and arrangement of the hinge members by which they are respectively adapted to be connected to the interior walls of the cover and crate, 15 whereby access to their fastening screws or nails, when the crate is closed, is prevented; second, to the location of the hinge pin of the respective hinge members at a distance above and at one side of the rear wall of the crate, 20 whereby the cover is free to be thrown back parallel with such rear wall without straining the hinge or its retaining fastenings; third, to the integrally formed hinges and lugs, which lugs, when the crate is open, are adapted to 25 reinforce the angular projecting ends of the hinge member and prevent them from becoming bent or broken by the weight of the cover; fourth, to the integrally formed lugs and hinge members, which are adapted, when 30 the crate is closed, to resist the lateral or forward strain upon the cover, whereby the liability of the cover becoming loosened from the crate is lessened and the strain upon the hinge pin is reduced to the minimum; fifth, 35 to the construction of the removable hinge pin in connection with a retaining arm, which arm is adapted, when the crate is closed, to engage against the inner wall of the crate, and thereby prevent the pin from being accidentally disengaged from the hinge members, 40 while such arm facilitates removing the pin when desirous to remove the cover from the crate; and sixth, to the construction of the integrally formed hinge member and corner 45 piece, which coöperate to reinforce and strengthen the crate and hold the hinge member in place.

My invention is further explained by reference to the accompanying drawings, in 50 which—

Figure 1 represents a vertical section of the upper left hand corner of the crate, showing the cover in its closed position, as seen from the opposite end of the crate; Fig. 2 represents a vertical section of the same corner shown in Fig. 1 with the cover shown open

and in a vertical position above the crate as it appears from the front of the crate; and Fig. 3 represents a similar view to that shown in Fig. 1, showing the cover in its extreme open position.

Like parts are identified by the same reference figures throughout the several views.

1 represents the rear wall of the crate, 2 one of the end walls, and 3 represents the 65 cover.

4 represents one of the cover supporting hinge members, which is connected to the inner wall of the cover by a plurality of nails or screws 5. 6 represents the other hinge 70 member, which is secured to the inner surface of the rear wall of the crate by a plurality of nails or screws 7. The hinge member 6 is preferably formed integral with a corner plate 8, which is adapted to be secured 75 to the inner surface of the end wall 2 of the crate by a plurality of screws or nails 9. It will be obvious that by thus securing the hinge members to the inner surface of the crate and cover, their fastenings cannot be 80 reached or disengaged when the crate is closed.

10 represents the hinge pin which is preferably formed integral with the arm 11, and the arm 11 is formed at an angle to the pin 85 whereby, when the cover is closed, it is adapted to engage against the corner plate 8 of the hinge member within the end wall of the crate, whereby it is impossible to remove the hinge pin when the crate is closed. The 90 arm 11 also serves as a convenient means of withdrawing the hinge pin from the hinge members, when desirous to remove the cover from the crate.

The hinge member 4 is provided with an 95 integrally formed lug 12, and the hinge member 6 is provided with an integrally formed lug 13, which lugs are respectively bent at right angles to the hinge member and serve to reinforce their angular projecting ends 100 directly beneath the hinge pin, whereby such angular projecting ends are prevented from being bent or broken by lateral pressure. Referring to Fig. 3, the lower edge of the lug 12 is adapted, when the cover is open, to rest 105 upon the upper edge of said cover, while the lower edge of the lug 13 is adapted to rest upon the upper edge of the rear wall 1 of the crate, whereby additional strength and rigidity are given to the respective protruding 110 ends of the hinge member. The hinge member 4 is provided with a laterally projecting

lug 14, which is adapted, when the cover is closed, to bear against the inner vertical wall of the corner plate 8, in which position it serves to resist the lateral strain of the cover toward the right and left and coöperate with the hinge pin in retaining the cover in place. The corner plate 8 is provided with a horizontal inwardly projecting lug 15, which is adapted, when the cover is closed, to contact 10 with the front edge of the lug 14, when said lugs coöperate to resist the forward strain upon the cover.

I have thus far shown and described the hinge members adapted to be connected with 15 one end of the cover and crate; it will however be understood that the opposite corner of such cover and crate are adapted to be provided with a similar set of hinge members; also that when the hinge members are in 20 place, the several angular lugs 12, 13, 14 and 15 coöperate to reinforce such hinge members and resist the strain to which the crate is ordinarily subjected.

Attention is called to the fact that the 25 hinge member 6 projects upwardly and rearwardly at an angle of about 45° to the inner wall of the crate, while the hinge member 4 projects upwardly and rearwardly past the rear edge of the cover 3, when the same 30 is in its closed position as shown in Fig. 1, whereby when the cover 3 is thrown back, as shown in Fig. 3, it is free to drop to a vertical position against the rear wall of the 35 crate without straining said hinge members or their retaining fastenings.

Having thus described my invention, what I claim as new, and desire to secure by Letters Patent, is—

1. The combination of a crate and cover, a 40 pair of integrally formed reversely inclined angular hinge members pivotally connected together at one end at a point substantially in line with the exterior surface of the crate and cover and having their opposite ends 45 rigidly connected with the interior surface of said crate and cover, said hinge members being adapted by their angular shape and the

location of their pivotal connection to permit the cover, when thrown back, to drop to the vertical behind said crate. 50

2. The combination of a crate and cover, a pair of reversely inclined angular hinge members pivotally connected together at one end and having their opposite ends rigidly connected with the interior surface of said crate 55 and cover, the angular ends of said hinge members being respectively provided with laterally projecting strengthening lugs located between their pivotally connected ends and the opposing edges of said crate and 60 cover, and adapted to strengthen and reinforce said hinge members.

3. The combination of a crate and cover, a pair of reversely inclined angular hinge members, a hinge pin adapted to connect the opposing ends of said hinge members together, the opposite ends of said hinge members being rigidly connected with the interior surface of said crate and cover, said hinge pin being provided with a laterally extending 70 arm adapted, when said cover is in its closed position, to engage the inner end wall of the crate and thereby retain said hinge pin in place.

4. A hinge comprising a lower, or crate 75 member, and an upper, or cover member, respectively secured to the interior walls of the crate and cover, the lower member being provided with a corner plate having an inwardly extending lug, and the upper member 80 provided with a laterally projecting lug, said last named lug being adapted, when the cover is closed, to engage at its side against the inner vertical wall of said corner plate and at its edge against the rear edge of said inwardly 85 projecting lug, whereby the cover when closed is supported against both forward and lateral pressure.

In testimony whereof I affix my signature in the presence of two witnesses.

GEORGE HENRY MAAS.
